UNITED STATES PATENT OFFICE

153,540

DESIGN FOR A SANDWICH VENDING
MACHINE

Carl Louis Otto, New York, N. Y., assignor to
Automatic Canteen Company of America, Chi-
cago, Ill., a corporation of Delaware

Application April 15, 1946, Serial No. 128,587

Term of patent 14 years

(Cl. D52—3)

To all whom it may concern:

Be it known that I, Carl Louis Otto, a citizen of the United States, residing at New York city, in the county of New York and State of New York, have invented a new, original, and ornamental Design for a Sandwich Vending Machine, of which the following is a specification, reference being had to the accompanying drawing, forming part thereof.

The single figure is a perspective view of a sandwich vending machine embodying my new design.

The side of the machine not shown is substantially the same as the side shown, while the top and rear thereof are plain.

I claim:

The ornamental design for a sandwich vending machine, substantially as shown and described.

CARL LOUIS OTTO.
